Des. 215,942

Patented Nov. 11, 1969

215,942

ANIMAL EAR TAG

Carlton W. Jacobson, Coteau, N. Dak. 58728

Filed Oct. 29, 1968, Ser. No. 14,216

Term of patent 14 years

Int. Cl. D30—99

U.S. Cl. D30—43

Fig. 1

Fig. 2

Fig. 3

Fig. 4

I claim:

The ornamental design for an animal ear tag, as shown.
